UNITED STATES PATENT OFFICE.

NELSON P. BOWSHER, OF SOUTH BEND, INDIANA.

FEED-MILL.

SPECIFICATION forming part of Letters Patent No. 528,070, dated October 23, 1894.

Application filed March 5, 1894. Serial No. 502,415. (No model.)

To all whom it may concern:

Be it known that I, NELSON P. BOWSHER, of South Bend, in the county of St. Joseph and State of Indiana, have invented certain new and useful Improvements in Feed-Mills; and I do hereby declare that the following is a full, clear, and exact description thereof, reference being had to the accompanying drawings, and to the letters of reference marked thereon, which form part of this specification.

This invention is an improved feed mill, which can be used for grinding grain alone, or as a corn and cob crusher and grinder, and its objects are to improve and simplify the means for adjusting the grinding cone in relation to the shell; to improve the construction of the cone and shell so that the escape of material being ground there-between will be retarded and it will be more thoroughly and finely comminuted; and to improve other parts of the machine, all of which will be hereinafter described in detail.

The invention consists in the novel combinations of parts summarized in the claims, and in the novel construction of parts shown, described and claimed.

Referring to the figures of the drawings by numerals, and to parts thereof by letters—
30 Figure 1 is a central vertical section through the complete machine. Fig. 2 is a view of the grinding shell detached. Fig. 2^a is a view of the grinding flange of said shell. Fig. 3 is a view of the grinding cone detached; Fig. 4, 35 a plan view of the case. Figs. 5 and 6 are detail views of the fastenings of the grinding cone sections. Fig. 7 is an enlarged detailed view of the joint in the sectional shaft E.

A designates the frustum of a hollow metallic cone, or semi-sphere, which constitutes the outer casing of the mill. From three sides of this casing, at bottom thereof, projects a base flange A' to which three equidistant legs A² are fastened, and which forms part of the top of a three sided box A³ in which the ground feed is deposited. The legs are fastened, to a base A⁴, when the machine is to be portable, or to the floor when the machine is to be permanently located. At the 50 upper edge of the casing, on the inner face thereof, is a series of lugs A⁵ adapted to assist in the crushing of cobs, &c. From the

upper edge of the casing, spring inwardly and upwardly curving arms a, uniting in a central ring a³, above the casing. From the 55 under side of said arms depend diagonally arranged lugs a², adapted to assist in crushing cobs, and in forcing material to the grinding surfaces. The upper surfaces of these arms are also studded or spined as at a' to assist in reducing the material.

B designates a hollow metallic cone frustum, forming the grinding shell, made of such size, relative to the casing, that it can be fitted thereinto, from below, as shown in Fig. 1. 65 This shell has a horizontal outwardly extending flange b at bottom, the lower surface of which is milled or serrated at b', the serrations extending from the inner edge of the flange, to near the outer edge thereof, but leaving a plain annular surface b² exterior to the serrations as shown. This flange also has lateral studs b³, through which pass the belts or rivets that fasten the shell to the casing.

The outer face of the shell may be polygonous and have a number of flattened or slightly dished facets B', and when the shell is fastened in place a number of small chambers will be formed between the opposed faces of shell and casing, into which chambers finely ground material will be forced and packed and thus a packed joint will be formed between the shell and casing, as indicated at X Fig. 1, and the shell be thereby kept fixedly in position within the casing, and its walls strengthened by the packings. The grinding shell need not necessarily be made polygonous. The space between the outer casing and this shell may be continuous, and all that is necessary to do is to cup out along the upper 90 edge small recesses whereby the material may be admitted to the free space between these two castings. It is immaterial whether the outer casing be cupped out or the edge of the shell be cut away; any way so as to admit of the feed or other material filtering and packing between the two parts as described. By this construction both strain on the shell and on the fastenings thereof to casing is relieved, and lateral movement of the shell within casing being prevented, the grinding surfaces 95

will be kept true.

The inner face of the shell is formed with graduated reducing and grinding teeth B², as

usual. The upper edge of shell B is just below the crushing lugs A⁵ of the casing.

The hollow grinding cone is formed of two parts, a top piece C, and bottom piece D. 5 Piece D is shaped much like and will fit easily within shell B. It has on its outer face a series of reducing teeth D² adapted to co-act with teeth B², and on its upper edge is a series of studs D⁶ adapted to co-act with studs A⁵ in crushing cobs, &c. On the lower edge of part D is a horizontal outwardly extending annular flange d, substantially parallel with flange b on shell B, toothed or serrated on its upper face, at d' and adapted to co-act with toothed flange b in making a further reduction of the material after it has passed between the grinding surfaces of the cone and shell. On the outer edge of flange d are bearing lugs d⁸ which are adapted to contact with 20 the surface b² of flange b', thereby preventing wobbling of the cone in the shell or the cone being raised so much in the shell as to cause the grinding surfaces to contact.

The parallel reducing flanges at the lower 25 edge of the grinding surfaces I deem a valuable feature of my invention. I do not confine myself to a strict parallelism of these corrugated surfaces. They should be substantially parallel. I would not lose the advantage of the rim by the simple alteration of 30 pitch of such surface. The main point is, that this flange extension being at an angle with the cone checks the discharge of the meal until it is further and finely comminuted.

In mills as heretofore constructed there is a crushing part, and a grinding part, but in addition to these parts, I have added the flange, just where the grinding surfaces end. 40 If these flanges were taken off my mill, it would still be as complete, as any heretofore constructed, but I add a flange which stands at an angle with the cone and which revolves in a horizontal plane opposite a parallel corner. 45 responding flange, the conical grinding surfaces opposed to each other, gradually converging, but the flanges remain substantially parallel and thus retard the delivery and escape of the material until the particles are 50 finely comminuted. They also retard the flow of material from between the conical grinding surfaces, which are thereby enabled to reduce the material to a finer state than would be possible if the flange on cone were omitted. 55 At the upper edge of the part D, is a short inwardly projecting flange D', from which project several short inwardly extending lugs D⁴, hereinafter referred to.

The part C of the cone is dome-shaped, and 60 is of such size that it can be fitted into the upper end of part D as shown in Fig. 1. It has an annular shoulder C' on which fits flange D', so that the exterior surfaces of the portions C, D, are continuous or flush at their joint, and part D is suspended on part C. 65 At intervals around shoulder C', corresponding to the lugs D⁴ are formed key slots hav-

ing a vertical portion c (open top and bottom extending through the part C), and a horizontal portion c' communicating at one end 70 with and extending laterally from, portion c. When the parts C, D, are to be united, part D is slipped over part C, and lugs D⁴ drop into portions c of the key-slots. One of the parts is then turned so as to cause the lugs 75 to enter the portions c' of the slots. Keys c³ shown in Figs. 3, 5 and 6 are then dropped in the vertical portions of the slots and secured by pins or wires fastened in openings in the lower ends of the keys. Thus the parts C, D, 80 are prevented from turning in relation to each other, and are secured together in a simple but effective manner.

On the upper face of part C is a number of upwardly projecting inclined lugs C² adapted 85 to co-act with the lugs a² in crushing cobs, &c., and also forcing the material outward and downward between the cone and shell.

From the center of part C rises a tubular stem C³, which extends through the ring a³, 90 by which the upper end of the cone is centered in the mill. The cone is supported however on a vertical shaft E, which may be formed in one or two parts, its lower end being stepped in a journal on a bar F suspended 95 transversely of and beneath the casing and cone by bolts f, or in other suitable manner, the bar F not being designed to be vertically adjusted for regulating the grinding of the material, which is effected by independently 100 rotating shaft E, as hereinafter described.

When shaft E is made in two parts as indicated in Fig. 7 it is divided in two parts just below part C. The thread E' is on the upper part E'' and just below the thread the 105 end of part E'' is squared as at E⁴ to enter a square socket E⁵ on the upper end of the lower part E. By this construction the threading at E' can be more economically effected and the square-socket joint makes the two-part 110 shaft sufficiently rigid for practical use.

G is a wheel shaped yoke having a central hub G', sitting over the ring a³ and an annular rim G², which rests upon an annular shoulder A⁶ on top of the casing, the hub and 115 rim being connected by arched spokes G³ which are studded on their under sides, as at G⁴, the studs coating with studs a' to crush the material in the hopper. To lugs g on this yoke is attached the sweep S when the 120 machine is driven by horse power, as it is principally designed to be. The stem C³ extends into hub G' and is interlocked therewith by means of flanges G⁵ in the hub, and recesses C⁴ on the stem, as shown so that the 125 cone is rotated by and with the yoke.

The shaft E which carries the cone has a threaded portion E' engaging corresponding threads in the lower end of stem C³, and its upper end extending above the stem and hub 130 G' is squared for the engagement of a wrench, or as shown, a hand wheel e, having a broad base which rests upon the hub G' or upon a plate e² interposed between the hand wheel

and hub as shown in Fig. 1. By rotating shaft E it screws the cone up or down, and thus the operator can readily regulate the grinding of the material without disturbing the bar F.

The hopper H is secured upon, and rotates with the yoke. The operation of the machine is similar to ordinary feed mills, except in the particulars above specified.

Having thus described my invention, what I claim as new, and desire to secure by Letters Patent thereon, is—

1. The combination of the dome portion of the cone, having a series of key slots around its periphery each consisting of an open vertical portion c and horizontal portion c', with the grinding portion of the cone having a series of lugs D⁴ corresponding to and adapted to engage the part c' of said key slots, and 20 the keys c³ for closing said slots and preventing withdrawal of the lugs therefrom, substantially as and for the purpose described.

2. In a grinding mill the combination of a grinding shell, and a grinding cone; with a shaft extending axially through said cone, and having a screw threaded portion engaging therewith, said shaft being rotatable independently of the cone, whereby the latter may be raised or lowered, by the screw thread 30 when the shaft is turned, substantially as and for the purpose specified.

3. The combination of the shell, a grinding cone, a shaft supporting said cone extending axially therethrough and having a screw-threaded engagement therewith, said shaft being rotatable with, and also independently of, the cone so as to raise or lower the latter by the threaded connection therewith, substantially as specified.

4. The combination of the casing, the grinding shell, and the grinding cone, with the shaft extending axially through said cone, having a screw threaded engagement therewith, and supporting it; means for rotating said cone and shaft, and means for rotating said shaft independently of the cone, substantially as described.

5. The combination of the casing, and a grinding shell fitted therein and secured thereto, the parts being constructed to form chambers between their opposed faces, open at top for the admission of packing; and a packing of suitable material in said chambers, substantially as set forth.

6. The combination of the casing, with a grinding shell fitted therein faceted on its outer face to form a polygonal series of chambers between it and the casing which chambers are adapted to be filled with packing, whereby the shell is rigidly kept in place within the casing and reinforced, substantially as specified.

7. In a grinding mill, the combination of the shell having a flange on its lower edge

toothed or serrated on its under surface; with the cone also having a flange on its lower edge serrated on its upper surface; one of said flanges having a continuous bearing surface on its serrated face exterior to the serrations and the other lugs on its serrated face exterior to its serrations, to prevent actual contact of the serrated portions of the flanges, substantially as described.

8. In a grinding mill the combination of the shell having a serrated flange on its lower edge and a smooth bearing surface exterior to the serrations and flush with the lower edges of the serrations; with a grinding cone having a serrated flange on its lower edge and a series of contact lugs exterior to the serrations adapted to engage the bearing surface on the upper flange to prevent engagement of the serrated portions of the flanges, substantially as described.

9. The combination of the casing, having a top ring, a shell secured in said casing, a cone centered in said shell, having a stem extending through said ring, and a wheel yoke mounted on the casing having a hub engaging said stem above the top-ring, said shell and cone having opposed parallel flanges on their lower edges; and a shaft carrying said cone having an adjustable screw threaded engagement therewith, substantially as set forth.

10. The combination of the casing, the grinding shell the cone centered therein, composed of upper and lower separable portions, the lower suspended on the upper portion, and a shaft carrying said cone, having a screw-threaded engagement therewith, for adjusting the latter; a wheel yoke mounted on the casing and engaging the stem of the cone, and means for rotating said carrying shaft independently of the cone, substantially as and for the purpose set forth.

11. The combination of the casing having a top ring, a shell secured in said casing, a cone centered in said shell formed of an upper dome portion supported on a vertical shaft, and a lower grinding portion suspended on the upper portion, said cone and shell having opposed parallel flanges on their lower edges, the vertical shaft supporting the cone having a screw threaded engagement with the cone for the purpose of adjusting it, means for rotating said shaft independently of the cone, and the wheel yoke mounted on the casing, and connections between said yoke and cone, all constructed and arranged to operate substantially as and for the purpose set forth.

In testimony that I claim the foregoing as my own I affix my signature in presence of two witnesses.

NELSON P. BOWSHER.
